SAFETY SHOE TOE

Bert Handelsman, West Bridgewater, Pa.

Application March 4, 1942, Serial No. 433,390

1 Claim. (Cl. 36—77)

The present invention relates to new and useful improvements in shoes, particularly for workmen in various industries, and has for its primary object to provide, in a manner as herein-after set forth, an article of this character comprising a safety toe shield or armor which is ventilated, thereby greatly promoting foot health and comfort in shoes of this type.

Another very important object of the invention is to provide a safety toe shield or armor of the character described for shoes comprising a single piece of material which may be produced in one operation.

Other objects of the invention are to provide a ventilated safety toe for shoes which will be comparatively simple in construction, strong, durable, highly efficient and reliable in use, light in weight, and which may be manufactured at low cost.

All of the foregoing, and still further objects and advantages of the invention will become apparent from a study of the following specification, taken in connection with the accompanying drawing wherein like characters of reference designate corresponding parts throughout the several views, and wherein:

Figure 1 is a view in side elevation of a shoe comprising a safety toe constructed in accordance with the present invention, the toe portion of said shoe being broken away in longitudinal section.

Figure 2 is a top plan view of the ventilated shield.

Figure 3 is a view in rear elevation of the shield.

Referring now to the drawing in detail, it will be seen that the embodiment of the invention which has been illustrated comprises a shield 1 of tempered steel or other suitable metal. As illustrated to advantage in Figure 1 of the drawing, the shield 1 is adapted to be incorporated in the toe portion 2 of a workman's shoe 3, to the shape of which toe portion said shield conforms.

The lower marginal portion of the shield 1 is

formed to provide an inturned flange or lip 4. Formed in the shield 1 is a plurality of openings 5.

It will thus be seen that a construction has been provided whereby the armored toe portion 2 of the shoe 3 will be thoroughly ventilated at all times. Of course, the perforations or openings 5 permit this ventilation. These openings 5 may be of any suitable size, shape and arrangement. The construction is such that the shield 1 may be incorporated in the shoe with a minimum of labor. Farmers, loggers, truckers and those engaged in various other occupations or who may be exposed to extremely cold weather may wear the ventilated safety toe as the perforations will permit the passage of moisture, allow the free circulation of air and prevent the metal from freezing the feet. Also, those employed in hot mills, brick kilns, ovens and other places where there is intense heat may wear the safety toe as the circulation of air through the ventilating openings will keep the feet from burning.

It is believed that the many advantages of a safety toe for shoes constructed in accordance with the present invention will be readily understood, and although a preferred embodiment of the device is as illustrated and described, it is to be understood that changes in the details of construction may be resorted to which will fall within the scope of the invention as claimed.

What is claimed is:

As a new article of manufacture, a safety device of the character described for shoes comprising a perforated metallic shield for slidable insertion for frictional retention in the toe portion of a finished shoe and conforming to the shape thereof, said shield being open at its bottom and rear end, and a downwardly and inwardly directed continuous flange on the lower marginal portions of said shield, said flange being tapered to a feather edge.

BERT HANDELSMAN.
